(57) CLAIM

The ornamental design for a combined cutting boards and knife holder as shown and described.

DESCRIPTION

FIG. 1 is a front perspective view of the combined cutting boards and knife holder showing my new design.

FIG. 2 is a front elevational view thereof;

FIG. 3 is a rear elevation view thereof;

FIG. 4 is the right side elevation view thereof; the left side elevation view is a mirror image of the right side thereof;

FIG. 5 is a top plan view thereof;

FIG. 6 is a bottom plan view thereof; and,

FIG. 7 is a bottom perspective view thereof.

The broken lines in the drawings depict environmental subject matter that forms no part of the claimed design.

1 Claim, 7 Drawing Sheets
